UNITED STATES PATENT OFFICE.

VERNON C. TASKER, OF WASHINGTON, DISTRICT OF COLUMBIA, ASSIGNOR
TO UNITED STATES ORDNANCE COMPANY, OF WASHINGTON, DISTRICT
OF COLUMBIA, A CORPORATION OF VIRGINIA.

BREECH-LOADING ORDNANCE.

SPECIFICATION forming part of Letters Patent No. 751,761, dated February 9, 1904.

Application filed February 7, 1903. Serial No. 142,356. (No model.)

To all whom it may concern:

Be it known that I, VERNON C. TASKER, a citizen of the United States, residing at Washington, District of Columbia, have invented certain new and useful Improvements in Breech-Loading Ordnance, of which the following is a full, clear, and exact description when taken in connection with the accompanying drawings, which form a part thereof, and in which—

Figure 1 represents a horizontal section through the breech of a gun embodying my invention; Fig. 2, a rear elevation of the same; Fig. 3, a vertical section of the same; Fig. 4, the same as Fig. 3, but with the breech-block revolved to its unlocked position; Fig. 5, a section through the breech-block and carrier on the line *cc* of Fig. 8; Fig. 6, a section on the line *aa* of Fig. 2; Fig. 7, a section on the line *bb* of Fig. 2; Fig. 8, a rear elevation of the gun and breech-block, the firing-case and carrier-hub being in section along the line *dd* of Fig. 1; Fig. 9, a plan view of the non-recoiling portion of the firing mechanism, the firing-handle *U* being in inoperative position and its operative position indicated by dotted lines; Fig. 10, a side elevation of the gun, showing the same parts as in Fig. 9; Fig. 11, a cross-section through the shaft *S* and hub of firing-handle; Fig. 12, a perspective view of the breech-block carrier; Fig. 13, a perspective view of the seat for the block-latch in the same; Fig. 14, a perspective view of the firing-case; Fig. 15, a section through the same, showing the locking-bolt *R*; Fig. 16, a plan view of the block-latch in place in the carrier; Fig. 17, a front elevation of the same; Fig. 18, a perspective view of the latch. Figs. 19 and 20 are rear and side elevations, respectively, of the gun, showing a modified form of block-latch and stop and a modified design of actuating mechanism for the firing-lock. Fig. 21 is a section on the line *gg* of Fig. 20. Fig. 22 is a side and end view of the washer *T* of Figs. 19, 20, and 21; and Fig. 23 is a vertical section through the block-latch in Fig. 19.

My invention relates to breech mechanism for guns, especially of the screw type, and

comprises improved means (a) for insuring that the gun cannot be fired before the breech-block is in its locked position; (b) for inserting or removing the firing mechanism from the rear by hand at any time; (c) for dismantling and assembling the breech mechanism by hand even though the block remains in its locked position in the gun; (d) for preventing rotation of the breech-block while swinging and in its open position; (e) for securing the operating-lever against accidentally opening when the breech is closed, and in improved construction generally.

The principal parts of the firing mechanism here shown are covered by my United States Letters Patent No. 710,124, dated September 30, 1902, and the extractor *X* here shown is covered by my United States Letters Patent No. 599,482, dated February 22, 1898.

Referring to the drawings, *A* represents a gun embodying my invention, having a central bore and powder-chamber *A'* and an eccentric breech-chamber *A''*, segmentally threaded, as at *A'''*. The breech-block *B* has correspondingly-threaded segments *B'* in the usual way, or other suitable engagement between breech-block and gun may be had.

C is a breech-block carrier hinged to the gun at *Q*, having a forwardly-projecting hub or journal *C' C''*, eccentric to the bore *A'*, but concentric with the breech-chamber. Said hub fits a corresponding central cavity of the breech-block, and the latter revolves thereon in locking and unlocking the breech with axial movement corresponding to the pitch of its threads *B'*.

To confine the block *B* in its movement on the carrier-hub *C' C''*, it is provided with a guide-lug *B''*, engaging a groove *C''*, cut in the carrier-hub. At one end of this groove is a run-out *C''*, extending forwardly, Figs. 5 and 12, through which the lug *B''* must pass in assembling or disengaging the block and carrier. The carrier-hub is pierced by the longitudinal chamber *C'' C''*, Figs. 1 and 5, eccentric to said hub but concentric with bore of gun. In this chamber is inserted and secured the firing-case *K*, carrying the firing mech-

anism proper. This latter consists (see Figs. 6 and 7) of the firing-pin D, spring E, spring-sleeve F, sear G, and pivoted arm H, all fully described and claimed in my previous Letters Patent No. 710,124 aforesaid. As therein set forth, the firing-pin D is normally held in retracted position by reason of the differential action of the opposite forces of its spring E upon the pivoted arm H, which arm normally acts rearwardly against said pin. When the arm H is caused to swing forwardly to fire the gun, its retractive action on the pin ceases; but the latter is then constrained by the sear G until the swinging arm has moved the sleeve F sufficiently forward to disengage said sear from the firing-pin, which thereupon flies forward and fires the gun.

The breech-block B has a perforation B³ in its front face, expanding rearwardly into a recess B⁴ just large enough to receive the head D' of the firing-pin. This recess and the perforation B³ are eccentric to the axis of the breech-block and so disposed as to be in axial alinement with the firing-pin D (and with the bore of the gun) when the block B is in its locked position, and obviously they will swing out of such alinement upon the rotation of the block to unlock, coming finally to the relation with firing-pin and bore illustrated in Fig. 4. It is therefore impossible for the firing-pin to go forward or fire the gun except the breech-block be in its completely-locked position, since in any other position the face B⁵, Fig. 4, surrounding the recess B⁴, would arrest the forward movement of the head D' of the firing-pin.

The chamber C⁶ in carrier-hub is provided with segmental lugs C⁷, interlocking with the corresponding lugs K' K² on the firing-case 40 to secure the same against rearward movement when assembled, the firing-case being removed from the carrier by a partial revolution and then withdrawal to the rear.

When the block B is in its locked position, the lug B², which guides it on the carrier-hub C', is opposite the forward run-out C⁴ therein and also extends into the chamber C⁶ in said hub. (See Figs. 5 and 8.) The lug K² on firing-case is traversed circumferentially by a groove K³, which embraces the lug B² as the firing-case is revolved to its locked position in the carrier, and thus prevents longitudinal movement between block and carrier by obstructing the run-out C⁴. Upon the removal 55 of the firing-case K or its partial rotation the block can freely move forward and off of the carrier-hub, or should the block be locked in the gun the carrier (upon removal of its hinge-pin Q') can be removed bodily to the rear and the mechanism completely dismantled, leaving only the block in the gun. This is of advantage in case the block should become jammed or stuck in the breech or if from any cause the breech mechanism can 60 not be opened by hand.

The rotation of the block B is effected by means of the operating-lever L, its toothed sector L', Fig. 3, engaging a similar toothed sector B⁶ on the rear face of the block, or other suitable means of rotation may be employed. As here shown, the lever L is mounted between the lugs C⁸ and C⁹, projecting rearwardly from the carrier, and pivots on the pin M, inserted from above and effectually secured against accidental removal by the insertion of the firing-case K. The end B⁷ of the sector B⁶ on the block meets the stop C¹⁰ on the carrier when block is unlocked and limits its rotation in that direction.

The latch N, resting on the surfaces C¹¹ and C¹² of the carrier and pivoting about the stud C¹³, locks the block B against rotation when in its unlocked position immediately upon the first movement of the block to swing out of the breech and until it is again in position 85 to engage the threads A³ therein. The latch is pressed forwardly by a spring N² resting in the socket N³ and reacting against the carrier. A boss N⁴ on the front face of the latch normally rests against the rear face of the gun, 90 the front face N⁵ then being in a position flush with the rear face B⁸ of the block when the latter is unlocked. Upon the first rearward movement of the block and carrier in swinging to the open position the latch N swings forward (being no longer held back by the gun) and its upper face N⁶ passes under a surface B⁹, Fig. 8, cut in the breech-block. The latter is then held against rotation in one direction by its stop C¹⁰ and in the other by the latch N. The whole system is then by the continued movement of the lever L swung about the hinge Q into the open position, the cam-surface C¹⁴ of the carrier actuating the extractor X to throw out the empty cartridge-case which 105 may be in the gun, and the surfaces C¹⁵ finally stopped by the surfaces A⁴ of the gun. As the carrier is swung again to its closed position the latch is forced back by its boss N⁴ coming in contact with the gun, and the front 110 face N⁵ is then just clear of the rear face of the breech-block, permitting the latter to revolve to its locked position. The latch N is confined vertically by a wing N⁷, which normally engages the slot C¹⁶ under the surface C¹¹ in the carrier. The latch may be pressed back by hand beyond the flush position it assumes when against the gun, and when so depressed its wing N⁷ is clear of the slot C¹⁶ and the latch can be slipped off of the stud C¹³ and 115 removed. Its spring N² remains in its socket N³, being retained by having an outturned end N⁸, resting in a depression or perforation in the socket, the elasticity of the spring permitting its insertion or removal by a slight 120 effort.

The firing-case K has at its outer extremity an arm K⁴, extending across the rear face of the carrier, carrying the shaft P and the locking-bolt R. The upper end of shaft P engages 130

the differential lever-arm H. Its lower end terminates in the free arm P', and it is held in place in the arm K⁴ of the firing-case by an elastic split ring P², lying in an annular groove 5 in the shaft P and expanding into a shallow groove in the firing-case. The locking-bolt or plunger R engages a hole C¹⁷ in the carrier when the firing-case is completely home, as will readily be understood from the drawings, 10 and it will be observed that the bolt R constitutes a lock for the entire mechanism, except the hinge-pin Q', since with this exception no part can in any way become detached or dismounted until this bolt be first withdrawn and the firing-case partially revolved. 15 The arm P' of the shaft P is for the purpose of rotating said shaft to fire the gun, and may be actuated thereto by any suitable means or be of any convenient form or direction. As 20 herein shown, the arm extends forwardly and is actuated by the pallet S', carried by a shaft S, journaled in bearings T T' on a non-recoiling portion Y of the mount or carriage. The shaft S is rotatively actuated by the spring V 25 to keep the pallet S' in its downward position.

A firing-handle U, projecting outwardly, is loosely mounted on the shaft S and is hinged at U' to permit of being folded rearwardly 30 against the bearing T, as in Fig. 9, its lug U² then engaging the slot T² and preventing rotation of the shaft S. It is retained in either 35 this safety position or the operative position of Fig. 2 by a spring U³ on the familiar principle of the jackknife. The hub U⁴ of the firing-handle has stop-surfaces U⁵ U⁶, limiting its rotation in either direction. A screw U⁷ in said hub has a projection entering the outer end of the slot S², Fig. 11, in the shaft 40 S, securing the latter against endwise movement and causing it to rotate against the resistance of the spring V when the handle U is depressed to fire the gun.

A horn or finger C¹⁹ on the carrier is normally just forward of the pallet S', and the latter is of helicoidal form, as shown. As the gun returns to position after recoil should the pallet still be in its upward position this horn C¹⁹ automatically deflects it to normal 45 position before it can again act upon the arm P', and if after this from any cause the handle U should be depressed before the breech is closed for the next shot the pallet S' is again automatically thrust into normal position by the horn C¹⁹ as the carrier swings shut. Thus the gun cannot be accidentally fired by the handle U being carelessly or accidentally held in depressed position between shots. In 50 firing the gun the pallet S' swings upwardly, and as the gun recoils the projection C¹⁹ acts on its underside and further deflects it slightly in order to pass to the rear, the slot S² in shaft S permitting this without further movement of the firing-handle U. The gun having been 55 fired, its recoil is arrested by any suitable

means, and this checking of its motion owing to the inertia of the operating-lever L tends to throw the latter rearwardly and open the breech. To prevent accidental opening from this or other causes, I provide a latch Z, Figs. 70 1 and 2, pivoting on the pin Z' in the operating-lever L and engaging a notched stud Z⁷ on the carrier C. The latch Z has a heavy arm Z², a lip Z³, rearwardly actuated by a spring Z⁴, and the inclined contact-surface Z⁵, 75 abutting against the notch Z⁶ of the stud Z⁷. As the operating-lever is opened by hand the inclined surface Z⁵ of the latch rides over this surface Z⁶ and causes the latch Z to rotate and the arm Z² to swing forwardly against the resistance of the spring Z⁴. The parts are so proportioned that there is a suitable moderate resistance to the opening of the lever L, and as the latter is closed again the latch Z readily rides over the end of the stud Z⁷ to its normal 80 position. (Shown in Fig. 1.) During recoil, however, when the checking or sudden arrest of rearward motion tends to throw the lever L violently to the rear, the same causes have a similar effect on the arm Z² of the latch, and 85 this arm acts with great leverage to maintain engagement of the surfaces Z⁵ and Z⁶, thus increasing the resistance to the rearward tendency of the lever in a degree measurably proportional to such tendency. 90

Another form of latch N⁹ for the breech-block is illustrated in Figs. 19 and 23, in which the latch when in engagement with the notch B¹¹ of the block acts as a strut and transfers the thrust of the breech-block directly to the 95 latch-pivot C²⁰. In other respects the operation of the two forms of latch is similar. The sector B¹⁰ on the breech-block prevents removal of the latch from its pivot until the block has been dismounted. In this arrangement the end of the sector abuts against the stop C²¹ on the carrier when the block is unlocked, the stop being of a somewhat different pattern.

Figs. 19, 20, 21, and 22 exhibit a modified 100 construction of the apparatus carried by the mount for actuating the firing-lock, by which it is possible to fire the gun when the latter has not completely returned to battery after recoil. It also obviates the necessity for the 105 horn C¹⁹ (shown on the carrier in Figs. 2 and 10) by providing for automatic release and return to position of the firing-shaft S³ after the firing-lever U⁸ has been depressed sufficiently 110 to fire the gun. To this end the pallet S⁴, 115 which engages the arm P' in firing, is extended rearwardly, and the shaft S³ is furnished with an independent return-spring V' and a releasing-latch S⁵, which is engaged by the hub U⁹ of the firing-handle during its movement in firing and released therefrom by the over-travel 120 of the handle. The bearing T³ has a central internal collar T⁴, engaging one end of the spring V', the other end of which engages the shaft S³ to keep it revolved to normal position. 125 130

The internal collar T^4 also engages one end of the lever-return spring V^2 , its other end engaging with the firing-lever hub and tending to maintain the latter in normal position. The 5 firing-lever hub has an annular projection U^{10} entering the bearing T^3 and partially cut away, forming a lip U^{11} , normally engaging the latch S^6 . (See Fig. 21.) A washer T^6 (shown separately in Fig. 22) abuts the end of the bearing 10 and carries a cam-lug T^8 , and its rotation is prevented by a dowel T^9 , engaging the bearing. The relation of parts is such that when the shaft S^3 , through the agency of the lip U^{11} , acting on the latch S^6 , has been rotated by the 15 firing-handle far enough to fire the gun the latch is depressed into the shaft by riding upon the cam-lug T^8 . This releases the shaft from the influence of the firing-lever and permits the spring V^2 to return it to normal position. 20 The firing-lever is stopped by the lugs U^{12} on its hub meeting the bearing T^3 , and upon subsequent release of downward pressure on the firing-lever it is restored to normal position by the spring V^2 . The latch S^6 then springs 25 again in front of the lip U^{11} in position to be again actuated by downward movement of the firing-lever.

I claim—

1. The combination with a breech-loading gun; of a breech-block revoluble eccentrically to the axis of the gun, a carrier, and a firing-hammer constantly supported in the axis of the gun by said carrier.
2. The combination with a breech-loading gun, of a breech-block eccentric to the bore of the gun, a carrier; and a normally retracted firing-hammer concentric with the bore of the gun and supported in the carrier, independently of the breech-block.
3. The combination with a breech-loading gun; of a revoluble breech-block eccentric to the axis of the gun, a carrier, and a firing-hammer supported by said carrier, the firing-hammer having a fixed alignment with the axis of the gun.
4. The combination with a breech-loading gun, of a carrier, a firing-hammer constantly supported in the axis of the gun by the carrier; and a revoluble breech-block eccentric to said axis and adapted by its rotation to prevent forward movement of the firing-hammer when the block is not locked and to permit forward movement when said block is locked.
5. The combination with a breech-loading gun, of a carrier, a firing-hammer constantly supported in the axis of the gun by the carrier, and a revoluble breech-block eccentric to said axis, said breech-block having an aperture aligned with the hammer when the block is locked.
6. The combination with a breech-loading gun, of a breech-block, a carrier supporting the breech-block, a firing device supported by the carrier independently of the breech-block; and means on the block engaging with the fir-

ing device to secure the block to the carrier in the locked position of said block.

7. The combination with a breech-loading gun, of a breech-block, a carrier supporting the breech-block, a firing device supported by the carrier independently of the breech-block; and means on the block engaging with the firing device to secure the block to the carrier in the locked position of said block, said firing device and breech-block being independently applied to and removed from said carrier.

8. The combination with a breech-loading gun, of a breech-block, a carrier supporting the breech-block, a firing device secured in the carrier independently of the breech-block; and means on the breech-block engaging with the firing device to secure the block to the carrier in the locked position of said block.

9. The combination with a breech-loading gun, of a breech-block, a carrier supporting said breech-block and interlocking therewith when the block is not locked, a firing device; and means on the block engaging with the firing device to secure the block to the carrier when the block is locked.

10. The combination with a breech-loading gun, of a carrier, a breech-block, and a firing device; said breech-block and firing device being independently supported by said carrier and interlocking with each other when the block is in its locked position.

11. The combination with a breech-loading gun, of a breech-block, a carrier for the breech-block, an inwardly-projecting stud in a recess in said carrier, a spring-actuated pawl pivoted on said stud and adapted to engage an abutment on the block to retain the latter in unlocked position, and a surface on the breech-block normally retaining said pawl on said stud.

12. The combination with a breech-loading gun, of a breech-block, a lever for operating said block; and means actuated by the movement of the gun for resisting the tendency of said lever to move, when said movement causes said tendency.

13. The combination with a recoil-mounted breech-loading gun, of a breech-block, a lever for operating said block; and an inertia-energized detent for the lever.

14. The combination with a breech-loading gun, of a breech-block, an operating-lever for the breech-block; and a detent for the operating-lever, the resistance of said detent being increased by an inertia-operated weight.

15. The combination with a breech-loading gun, of a breech-block, a lever for operating the breech-block; and inertia-operated means actuated by movement of the gun for restraining said lever when said movement causes the lever to have a tendency to open the breech.

16. The combination with a breech-loading gun, of a breech-block, a lever for operating the breech-block; and inertia-operated means actuated by movement of the gun for restrain-

ing said lever when said movement causes the lever to have a tendency to open the breech, the restraining effect of said means increasing with increased tendency of the lever to open 5 the breech.

17. The combination with a breech-loading gun, of a carrier, a breech-block, an operating-lever for the breech-block, a latch pivoted on the operating-lever, an engaging surface 10 on the carrier for the latch; and an inertia-operated arm for increasing the resistance of the latch and integral therewith.

18. The combination with a breech-loading gun, of a breech-block, a carrier for the breech-block, a lever for operating the breech-block, a stud on the carrier having a notch, a latch pivoted on the lever and having a surface contacting with the notch; and a heavy free arm formed integral with the latch and extending 20 transversely to the gun.

19. The combination with a breech-loading gun, of a breech-block, a breech-block carrier having a hub, said hub having a circumferential groove merging with a longitudinal 25 groove, a lug on the breech-block traveling in said groove, means for rotating the breech-

block; and means for obstructing the longitudinal groove to prevent egress of the lug of the breech-block.

20. The combination with a breech-loading gun, of a breech-block, a carrier having a hub on which the breech-block is mounted, said hub having merging longitudinal and circumferential slots, a lug on the breech-block movable in the slots, a firing-casing inserted in the 30 hub of the carrier, a lug on the casing for obstructing the longitudinal slot of the hub to prevent egress of the lug of the breech-block; and means for retaining the casing in the hub.

21. The combination with a breech-loading gun, of a hinged carrier having a hub; and a breech-block interlocking with said hub when the block is not locked and unlocking therefrom when said block is locked.

In testimony whereof I affix my signature, 45 in the presence of two witnesses, this 6th day of February, 1903.

VERNON C. TASKER.
